DESIGN FOR AN ULTRA-VIOLET SHOE STERILIZER

Norman A. Whittaker, Seattle, Wash.

Application June 14, 1941, Serial No. 101,466

Term of patent 3½ years

To all whom it may concern:

Be it known that I, Norman A. Whittaker, a citizen of the United States, residing at Seattle, in the county of King and State of Washington, have invented a new, original, and ornamental Design for an Ultra-Violet Shoe Sterilizer, of which the following is a specification, reference being had to the accompanying drawing, forming a part thereof.

In the drawing:

Figure 1 is a view in side elevation of the sterilizer showing my new design;

Fig. 2 is a view in end elevation thereof; and
Fig. 3 is a top plan view of the same.

I claim:

The ornamental design for an ultra-violet shoe sterilizer, as shown.

NORMAN A. WHITTAKER.
